ROBERT N. WAGENER, OF CANTON, OHIO.

WATER-HEATER.

1,244,924.

Specification of Letters Patent. Patented Oct. 30, 1917.

Application filed February 23, 1916. Serial No. 79,882.

To all whom it may concern:

Be it known that I, ROBERT N. WAGENER, a citizen of the United States, residing at Canton, in the county of Stark and State of Ohio, have invented certain new and useful Improvements in Water-Heaters, of which the following is a specification.

The invention relates to a sectional heater for water for use in a steam or hot water heating system, and the object of the improvement is to expose a maximum surface of water walls to the action of the heat, and to provide an intervening hollow baffle between the combustion chamber and flues for obtaining the most intensive action of the heat.

This object and other ancillary advantages are attained by the construction and arrangement of the heater walls and water sections illustrated in the accompanying drawings forming part hereof, in which—

Figure 1 is a front elevation of the heater showing the right side broken away and the sections therein rotated upward upon the axis of the lower connecting nipples, to show an under side view of the rotated sections.

Fig. 2, a longitudinal vertical section, showing a side elevation of one of the water sections of the heater;

Fig. 3, a section on line 3—3, Fig. 2, of one of the intermediate water sections;

Fig. 4, a section on line 3—3, Fig. 2, of one of the end water sections;

Fig. 5, a section on line 5—5, Fig. 2, of one of the intermediate water sections; and

Fig. 6, a section as on line 3—3, Fig. 2, of a modified form of an intermediate water section.

Similar numerals refer to similar parts throughout the drawings.

The heater is made of a number of hollow water sections 1, 1^a and 1^b, connected together at their upper ends by the series of nipples 2, and at their lower ends by the series of nipples 3, by means of which the interior of one water section communicates above and below, with the interior of another section; so that the water or steam can circulate freely in and among the several sections.

The forward portion of the lower ends of the intermediate water sections 1^a and 1^b are shaped to form the combustion chamber 4, below which may be provided grate bars 5 for carrying the coal 6 or other form of

fuel. For this purpose the forward portions of the lower ends of the intermediate water sections extend first horizontally rearward, as at 7, above the combustion chamber 4, thence diagonally downward and rearward, as at 7^a, at the back of the upper portion of the combustion chamber, thence rearward with a slight downward inclination, as at 7^b, to a point above the rear end 65 of the grate bars, and thence directly downward to the lower end of the section.

The outer side portion 8 of each end section is extended downward to the base panels to form the sides of the combustion chamber 4, and a front plate, which may be in the form of a hollow water wall 9 is provided for closing the front of the combustion chamber, which is thus formed between the outer walls of the side sections and the forward portions of the lower ends of the intermediate sections as described above.

Certain portions of at least one side wall of each water section are recessed or offset inward to form the combustion flues 10, 80 the mixing flues 11, the forward smoke flue 12, the rearward smoke flue 13, the outlet smoke flue 14 leading to the smoke manifold 15, and the hand holds 16, when the water sections are assembled side by side. 85

The recesses forming these flues, excepting the smoke outlet flue 14, are located at a substantial distance below the upper ends 17 of the sections, thus forming the water or steam chambers 18 of substantial length, 90 depth and width, in the upper end of each section, corresponding to the steam dome of an ordinary steam boiler.

Extending first diagonally downward from the middle portion of the water chamber 18, and thence directly rearward at an interval above the lower end of each section, is provided the hollow flue baffle 19 and 19^a, which divides the combustion and mixing flues from the smoke flues. 100 The hollow of this baffle communicates with and forms part of the water chamber in each section, and it is evident that the walls of the baffle are subject throughout their extent to the action of the heat in these several flues.

Along the intermediate diagonal portion 7^a of the lower end of each water section, is provided the laterally extending hollow baffle 20, which baffle is entirely surrounded 110 above, in rear and below by the combustion and mixing flues and in front by the

combustion chamber and thus may be said to intervene between said flues and chamber. The hollow of this baffle communicates with and forms part of the water chamber in each section, and its end and side walls are therefore subject to the direct, and thus the most intense action of the heat in the combustion chamber and combustion flues.

In the middle of the rear end part of each section, is provided the horizontal hollow baffle 21, which forms the division between the forward and rearward smoke flues, and may also divide the upper and lower hand holds 16, as shown in Fig. 2, which hand holds are normally closed by the door 22. And finally, the inlet pipe 23 leads into the lower end of one water section and the outlet pipe 24 leads out of the upper end of one of the water sections, for circulating water or steam through the heater.

By reason of the peculiar formation of the flues in the sides of the sections by recessing or offsetting the same inwardly, it will be evident that each of the baffles is in direct lateral communication with the adjacent water chamber proper, so that when the water in the baffles becomes highly heated or steam is produced, on account of the subjection of the baffles to the more intense heat from the combustion chamber, such steam or water is permitted to rise immediately to the upper portion of the chamber and thus give way to the cooler waters entering from the chamber proper.

It will be understood that the slight intervals between the adjacent rim portions and the edges of the baffles of each water section, are closed by a fire cement in the usual manner employed in heaters of this type, thus closing these intervals and completing the formation of the combustion chamber and the several flues as herein described.

In the use of the heater with coal, coke or other like fuel 6, it is evident that the same will naturally fill the combustion chamber up to the lower end of the intervening baffle 20, thus forming a partial closure of the lower sides of the mixing flues 11; and that the partially consumed fuel will accumulate below and to the rear of the intervening baffle, while the freshly fed fuel will be located in front thereof.

The more active flames of fire and gases of combustion will rise directly upward and rearward against the intervening baffle 20, and around the upper ends thereof into the upper ends of the combustion flues and against the lower walls 23 of the water chambers 10; thence these flames and gases pass rearward and downward through the combustion flues between the forward wall of the flue baffle 19 and rearward wall of the intervening baffle 20, at the lower end whereof they join and mix with the additional air and gases which find their way

through the partly consumed fuel located on the rear end of the grate bars; whence the combined gases will be carried directly rearward through the mixing flue 11 and thence first forward and then rearward through the smoke flues 12 and 13, and thence upward through the outlet flue 14, so that a substantially complete combustion can be accomplished before the gases finally leave the heater through the smoke manifold 15, thereby utilizing substantially all of the heat units arising from the complete combustion of the fuel gases.

It is evident that the peculiar location of the intervening baffle of each water section and its arrangement with reference to the chamber and flues which entirely surround it, subjects this baffle and the water contained in the hollow thereof, to the most intense action of the heat arising from the burning of the fuel and the initial combustion of the gases thereof; and that the location and arrangement of the mixing and smoke flues is such that all the heat units arising from the complete combustion of the fuel gases will be brought into play against the various walls of the water sections for heating the water contained in the hollow baffles and chambers thereof.

In the modified form of one of the intermediate water sections shown in Fig. 6, the side walls thereof are offset or recessed on both sides to form the several flues, which is an obvious modification which does not depart from the general idea or spirit of the invention.

I claim:

1. A water heater including a series of hollow sections forming water chambers having the forward parts of the lower ends shaped to form a combustion chamber, and having their side walls offset inward to form combustion flues and mixing flues, with a hollow baffle in direct lateral communication with the water chambers intervening between and being entirely surrounded by the combustion chamber and said flues.

2. A water heater including a series of hollow sections forming water chambers having the forward parts of the lower ends shaped to form a combustion chamber, and having their side walls offset inward to form combustion flues, mixing flues and smoke flues with hollow baffles between said flues, and a hollow baffle on each section in direct lateral communication with the water chambers intervening between and entirely surrounded by the combustion chamber, and the corresponding combustion and mixing flues.

3. A water heater including a series of hollow sections forming water chambers having the forward parts of the lower ends shaped to form a combustion chamber, and having their side walls offset inward to form combustion flues, mixing flues, and smoke

flues extending first forward and then rearward, with hollow baffles between said flues, and a hollow baffle on each section in direct lateral communication with the water chambers intervening between and entirely surrounded by the combustion chamber, and the corresponding combustion and mixing flues.

4. A water heater including a series of hollow sections forming water chambers having the forward parts of the lower ends shaped to form a combustion chamber, and having their side walls offset inward to form combustion flues, mixing flues, and smoke flues extending first forward, then rearward and then upward, with hollow baffles between said flues, and a hollow baffle on each section in direct lateral communication with the water chambers intervening between and entirely surrounded by the combustion cham-

ber, and the corresponding combustion and mixing flues.

5. A water heater including a series of hollow sections forming water chambers having the forward parts of the lower ends shaped to form a combustion chamber, and having their side walls offset inward to form combustion flues, mixing flues, and smoke flues extending first forward, then rearward and then upward, with hollow baffles between said flues, and a hollow baffle on each section in direct lateral communication with the water chambers intervening between and entirely surrounded by the combustion chamber, and the corresponding combustion and mixing flues, and a smoke manifold communicating with the several upward smoke flues.
